HOUSEHOLD IMPLEMENT

Filed July 14, 1928

Emma Martin,
INVENTOR

UNITED STATES PATENT OFFICE

EMMA MARTIN, OF LOS ANGELES, CALIFORNIA

HOUSEHOLD IMPLEMENT

Application filed July 14, 1928. Serial No. 292,835.

This invention relates to improvements in implements and especially household devices and has for its objects to provide a simple, efficient and inexpensive post having 5 a lifting and a pulling hook.

One of the objects of this invention is to provide an implement particularly designed for the purpose of lifting picture frames, mirrors and the like off from hooks or nails 10 to which they are secured and by which they are suspended upon a wall or support.

Another object of this invention is to provide a convenient household implement with simple means for lifting objects supported 15 upon walls or for pulling down curtains and the like.

A still further object of my invention is to provide a form of implement characterized by the feature of providing one hook 20 on one side at the upper end of the implement, pointing downwardly for pulling down objects or movable fixtures, and another hook opposite to the first hook and pointing upwardly for lifting or pushing 25 up fixtures and the like.

In the performance of various household duties it becomes necessary at times to remove mirrors, picture frames and the like from walls and the object thus removed 30 must be supported while it is being removed. To this end my invention provides an implement which is strong, durable and which can be easily manipulated for lifting frames from walls.

35 With the above and other objects in view my invention consists in the combination, arrangement and details of construction disclosed in the drawings and specifications, and then more particularly pointed out in the appended claims.

In the drawings, wherein similar reference characters designate similar parts throughout the respective views,

Figure 1 is a side elevation of my invention,

Figure 2 is a side elevation of a modification of my invention,

Figure 3 is a vertical section of a wall showing my invention applied in use for 50 pulling down window shades,

Figure 4 is a vertical elevation of a wall showing the manner of lifting a frame from the wall by means of my present invention.

Referring to the drawings which are merely illustrative of my invention 10 designates 55 a suitable rod, stick or post of suitable material and strength, which may be polygonal or round in cross section.

This post is cut away and sliced to provide the slit 12 and an arm or severed portion 15. In order to form a hook for lifting purposes out of the arm 15 a spacer 13 is arranged between this arm and the adjacent surface of the post so that the outermost end of this arm flares outwardly providing 60 an upwardly pointing hook. This same arrangement of post and severed arm is shown in Figure 2 in conjunction with the hook 16 secured to the topmost end of the post, where the hook shown curves around 65 and points towards the lower end of the post.

From the foregoing description the operation of the device is as follows. Figure 3 shows the device in use for pulling down 70 window shades and the like. The hook 16 or 17 or 26 will be used for this purpose; when this hook is introduced into the ring handle of the shade and pulled downwardly it follows that the window shade must come 75 down with it. On the other hand, as illustrated in Figure 4 the handle post 10 may be taken and its forked or slit end 15 presented against the wires holding the picture frame or the like suspended upon a wall 80 or other surface; the wires may be lifted so as to rest and be supported upon the hook 22, or 25 or 15 when the picture frame no longer is supported upon its moorings. Thus one and the same implement is 85 designed to be used for either lifting the picture frame or for the purpose of pulling down a window shade or the like.

I do not mean to restrict myself to the exact details of construction herein disclosed 90 but cover all variations falling within the purview of the appended claim.

What I claim and desire to secure by Letters Patent is:—

In combination with a post slit at one end

to provide a severed arm, and a spacer interposed between the post and the arm whereby to space the arm laterally outwardly to provide a lifting hook, and a hook having its shank projecting into one end of the post.

In witness whereof she has hereunder set her hand this eleventh day of April, 1928.

EMMA MARTIN [L. S.]
